UNITED STATES PATENT OFFICE.

QUINCY A. BRACKETT, OF PITTSBURGH, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

Application filed January 24, 1921. Serial No. 439,391.

To all whom it may concern:

Be it known that I, QUINCY A. BRACKETT, a citizen of the United States, and a resident of Pittsburgh, in the county of Allegheny and State of Pennsylvania, have invented a new and useful Improvement in Systems of Control, of which the following is a specification.

My invention relates to wireless telegraphy and more especially to means for controlling the radiation of electrical energy in the form of electro-magnetic waves.

The object of my invention is to provide means whereby the radiation of energy from an antenna circuit of a wireless-transmission system may be selectively controlled by means of an absorbing, non-radiating circuit operatively coupled to the antenna circuit.

20 The present systems of control suitable for high-power, high-frequency generator systems employ controlling circuits which are connected in shunt relation to the source of energy that is employed to energize the radiating systems. With this system of control, the currents traversing the shunt circuit may be modulated by varying the impedance of an electro-magnetic device which is connected in said circuit, thereby causing 30 similar modulations in the energy supplied to the antenna circuit.

The particular disadvantage of the present systems of control, however, are the continuous radiation of energy during the non-signaling period and the radiation of energy at two wave lengths during the signaling period.

According to my invention, I provide means which permits of the radiation of 40 energy at one wave length during the signaling period and effectually renders the radiating system non-effective during the non-signaling period.

The desired result is accomplished by 45 employing a non-radiating circuit which is operatively coupled to the antenna circuit. By varying either the capacitance or inductance of the absorbing or non-radiating circuit, it may be selectively rendered resonant or non-resonant to the generator frequency, to selectively control the radiation of energy from the antenna circuit.

My invention may best be understood by

reference to the accompanying drawings, in which:

55 Figure 1 is a diagrammatic representation of circuits and apparatus embodying my invention.

Figs. 2, 3, 4 and 5 are similar views showing alternate arrangements to that of Figure 1.

60 Like numerals are employed to designate like parts having similar functions.

Referring to Figure 1, a source of energy 1 is operatively connected to a radiating 65 circuit through coupling coils 2 and 3, respectively. The radiating circuit includes an antenna 4, the coupling coil 3 and a ground lead 5.

An absorbing circuit 6 is operatively connected to the radiating circuit and the supply circuit through a coupling coil 7 and coupling coils 3 and 2, respectively. This circuit comprises the coupling transformer 7, an inductor 8, a pair of condensers 9 and 11, a key 12 for shunting condenser 11 and an adjustable resistor 13.

The arrangement shown in Fig. 2 differs from that of Figure 1 in the parallel connection of a pair of condensers 14 and 15 in the absorbing circuit 6. The key 12 is connected in series with the condenser 14. The capacitance of condenser 14 is small in comparison with that of condenser 15.

The arrangement shown in Fig. 3 differs from those of Figs. 1 and 2 in that the period of the absorbing circuit 6 may be varied by shunting a portion of the inductor 8 by means of the key 12.

90 Referring to Fig. 4, the arrangement shown differs from that of Fig. 3 in that the inductance of the circuit is controlled by varying the magnetic flux through a pair of coils 16 and 17 which are included in the absorbing circuit 6. An electromagnet device 18, which may be employed to effect the desired changes in the period of the absorbing circuit, comprises a pair of cores 19 and 21, together with the magnetizing 95 windings 16 and 17. A third core 22, which is disposed between the pair of cores 16 and 17, is provided with a controlling winding 23. The permeability of the magnetic circuits through coils 16 and 17 may be selectively controlled by means of a circuit

which comprises a source of energy 24 and the controlling winding 23.

Referring to Fig. 5, the system here shown differs from those of the previous arrangements in that means are provided for simultaneously tuning the absorbing circuit and detuning the antenna circuit with respect to the generator frequency. The electromagnetic device 18 is similar in construction to that of Fig. 4. The arrangement of the circuits is also similar to that of Fig. 4, with the exception that the magnetizing winding 17 is included in the antenna circuit. The constants of the antenna and absorbing circuit are so adjusted that, with the key 12 open, the absorbing circuit is tuned to the generator frequency and the antenna circuit is detuned.

In the operation of my system, with the absorbing circuit in resonance with the high-frequency alternating currents traversing the antenna circuit, the energy absorbed therefrom is a maximum.

Referring to Fig. 1, with the key 12 open, the absorbing circuit is resonant to the generator frequency, thereby causing substantially all of the power supplied to the antenna circuit to be absorbed by the non-radiating absorbing circuit.

Upon closing the key 12, the condenser 11 is shunted to detune the absorption circuit, thereby permitting a maximum amount of radiation from the antenna.

The operation of the arrangements shown in Figs. 2, 3 and 4 is substantially the same as that of Fig. 1. The difference between the systems shown in the several figures consists in the utilization of various key-controlled means for effecting changes in the period of the absorbing circuit.

Referring to Fig. 5, with constants of the antenna and absorption circuits so adjusted that, upon opening the key 12, the absorption circuit is rendered resonant to the generator frequency and the antenna circuit is rendered non-resonant, substantially no energy is radiated by the antenna circuit. The energy that is absorbed by the non-radiating circuit may be dissipated as heat in the resistor 13.

Upon closing the key 12, the flux produced by the magnetizing winding 23 so varies the permeability of the magnetic circuits through the coils 16 and 17 that the antenna circuit becomes tuned to the generator frequency coincident with the detuning of the absorbing circuit. Thus, with key 12 closed, a maximum amount of energy is supplied to the antenna.

The particular advantage of my arrangement is in the provision of a simple, inexpensive control system for selectively controlling the radiation of energy from an antenna of a wireless transmission system.

While I have shown several embodiments

of my invention, it is still capable of various changes and modifications within the scope of the appended claims. I desire, therefore, that only such limitations shall be imposed thereon as are indicated in the appended claims.

I claim as my invention:

1. In a wireless transmission system, the combination with a supply circuit and a radiating circuit, of an absorbing circuit operatively associated with said supply circuit, magnetic means interlinking said radiating circuit and said absorbing circuit, and means operating on the magnetic characteristics of said magnetic means for substantially simultaneously rendering said radiating circuit effective and said absorbing circuit non-effective, and vice versa. 75

2. In a wireless transmission system, the combination with a supply circuit and a radiating circuit including a coil, of an absorbing circuit also including a coil and operatively associated with said supply circuit, a magnetic core interconnecting said radiating and absorbing circuit coils and means for varying the magnetic characteristics of said core, whereby said radiating and absorbing circuits may be selectively rendered effective or non-effective. 85

3. In combination, a work circuit, a supply circuit therefor, and an idling circuit, said idling circuit being operatively associated with said supply circuit, coils individual to said work circuit and to said absorbing circuit a magnetizable core for said coils, and modulating means for varying the magnetic characteristics of said core. 90

4. The combination with a source of oscillatory currents, of a tuned work circuit, a tuned absorbing circuit operatively associated with said source, tuning coils individual to said work and absorbing circuits, a magnetizable yoke member for said coils, a modulating magnetizing coil for said yoke member, and a modulating circuit operatively associated with said last-mentioned coil, whereby said work circuit may be rendered effective and said absorbing circuit non-effective, and vice versa. 100 105

5. In a radio signaling system employing oscillatory currents, a tuned work circuit including energy translating means, a tuned idling circuit including means for producing the effect of a resistance having a desired relation to that of said energy translating means, tuning coils individual to said circuits, a common magnetizable yoke member for said tuning coils, and a modulating magnetizing coil also associated with said yoke member operable to tune said work circuit and to detune said idling circuit, and vice versa. 115 120

6. The combination with a source of oscillatory currents, of a tuned work circuit adapted to be connected thereto, energy 125 130

translating means included in said work circuit, a tuned auxiliary circuit also adapted to be connected to said source, coils individual to said work and auxiliary circuits, 5 an iron core transformer having a plurality of individual core portions to provide one for each coil, and an auxiliary winding adapted to serve as modulating means operable to oppositely vary the tuning of said 10 circuits.

7. The combination with a source of oscillatory currents, of a tuned work circuit adapted to be connected thereto, energy translating means included in said work cir-

cuit, a tuned auxiliary circuit also adapted 15 to be connected to said source, coils individual to said work and auxiliary circuits, a modulating coil, an iron core transformer having a plurality of individual core portions to provide one for each coil, and a 20 modulating circuit for said modulating winding, whereby said work circuit may be detuned and said auxiliary circuit tuned, and vice versa.

In testimony whereof, I have hereunto 25 subscribed my name this 14th day of January, 1921.

QUINCY A. BRACKETT.
